CLASP FINDING

Anthony R. Saccoccio, Cranston, R. I., assignor to
Aro-Sac, Inc., a corporation of Rhode Island

Application April 4, 1955, Serial No. 498,930

3 Claims. (Cl. 24—252)

This invention relates to a clasp of the type used in jewelry, such for instance as for mounting an ornament on the ear or for mounting an ornament on the dress of the wearer.

Clasps of the character here referred to are usually formed by the securing of a finding to an ornament. The findings are usually made by a manufacturer who specializes in the formation of this mechanical part and are then sold to be assembled on ornaments of different characters by an ornament manufacturer. The invention in this application deals more particularly with the finding which is to be sold to the ornament maker to be attached thereto and then sold complete as a clasp.

In this type of device the ornament to which the finding is attached forms one jaw, while a finding provides the other jaw of the clasp. The connection between the finding and the ornament is usually made by solder, and some difficulty is sometimes encountered in the relative positioning of the parts of the finding that they may assume a proper relation for connection to the ornament, this occurring because of a spring action which tends to swing the jaw of the finding beyond a position which it would assume when attached to the ornament and this occurring because of the desirability of having the spring press the finding jaw so that it will positively engage the ornament.

One of the objects of this invention is to provide a stop which will positively and definitely position the two moving parts of the finding that it may be attached to the ornament.

A more specific object of the invention is to provide in the finding a stop for limiting the swinging movement of the finding jaw relative to the mounting member in two directions whereby the jaw may assume and be held in either one of two extreme positions, either of which may be advantageous in soldering or securing of the finding to the ornament, one position being more desirable for the attachment to one character of ornament while the other position is more desirable for another character of ornament.

Another object of the invention is to provide a construction of finding in which a minimum amount of stock is used so that when stock of precious or semi-precious metals is used, there will be a minimum amount of this material necessary in the device.

Another object of the invention is to provide a hole or opening which serves the advantageous purpose of reducing the amount of metal in the device and also of providing by reason of the edge of the opening an advantageous abutment for limiting the movement of the jaw in one direction.

Another object of the invention is to provide for the adjustment of pressure that a spring tongue will have on the strap which it engages so that the pressure on the lobe of the ear may be adjusted.

Another object of the invention is to provide a device which will be of light weight so that when used as an

2

ear attachment, the weight on the ear may be at a minimum.

Another object of the invention is to provide an arrangement so that in opening the clasp, the spring which serves to move the clasp to closed position cannot be damaged by persons not mechanically inclined and who have the tendency to play with movable parts or to accidentally tend to move them in the wrong direction and apply greater pressure than the parts are designed to stand.

With these and other objects in view, the invention consists of certain novel features of construction as will be more fully described and particularly pointed out in the appended claims.

In the accompanying drawings:

Figure 1 is a sectional view showing the finding in closed position and in full lines with an ornament illustrated in dotted lines;

Figure 2 is a view similar to Figure 1 but illustrating the device as swung to open position;

Figure 3 is a perspective view of the mounting member, looking at it in one direction;

Figure 4 is a perspective view of the mounting member, looking at it in the opposite direction;

Figure 5 is a perspective view of the jaw and the spring tongue which is of the same piece of material as the jaw.

With reference to the drawings, I provide a mounting member designated generally 10 and shown by itself in Figures 3 and 4. This mounting member comprises a bottom wall 11 with end walls 12—12 extending at generally right angles to the bottom wall and spaced apart by the bottom wall. This structure also has a side wall 13 also extending at generally right angles to the bottom wall and at right angles to the end walls 12. This structure is all formed from sheet stock bent to the positions indicated. The side wall 13 serves as a mount for the ornament 14 shown in dotted lines in Figures 1 and 2. This ornament may be of any desired form or shape and is usually attached to the side wall 13 by solder and forms one of the jaws of the clasp.

The bottom wall 11 is cut out as at 15 in a large portion of its area, which is of importance when precious or semi-precious metal is used, as the amount of stock removed from this opening is of substantial value. This also provides lightness in weight, which is of importance when the device is to be used for attachment to the ear, as minimum weights are often of importance. This opening or cut-out 15 is spaced from the convexly curved edge 16 of the bottom wall so as to provide a strap 17 extending between the end walls 12. This strap performs an important part of the invention and is offset substantially the entire length of the opening 15 as at 18 but in any event will be offset in a length at least the width of the spring tongue of the finding jaw to be later described, which is to engage it, and this offset will also be substantially the thickness of the spring tongue which is to engage it and also serves to guide the spring tongue against the edge 19 of this opening, which is the edge opposite the opening from that along which the strap 17 extends. Thus, this edge 19 serves as an abutment.

The jaw of the finding is designated generally 20 and is shown in perspective alone in Figure 5. The body portion 21 of this jaw is provided with trunnions 22 which are pivotally mounted in the openings 23 in the side walls 12, while this body 21 is also slit as at 24, 24 along parallel lines spaced apart sufficiently to provide a tongue 25 between these slit portions and is of an extent longer than the body portion carrying the trunnions 22. This tongue has a straight line inner surface to contact the convexly curved edge 16 of the strap 17 to

assist in easy movement and is curved lengthwise to afford more even spring tension as the jaw is moved about its pivot. The end portion 26 of this tongue is provided with a flange 27 extending generally at right angles thereto, while the inner surface of this tongue is corrugated as at 28 so as to provide a series of notches extending generally parallel to the axis of the pivot trunnions 22. This portion 26 of the tongue engages the strap 17 and is of a width a little less than the extent of the offset of this strap and is of a thickness substantially the thickness of the offset of the strap.

As shown in Figure 1, the jaw 20 is in substantially closed position with the tongue 25 having its end portion engaging the strap 17 and prevented from further closing movement by reason of the flange 27 forming a hook portion to engage the strap 17, thus preventing swinging movement of the jaw 20 with reference to the side wall 13 of the mounting member so that even though the spring is acting to swing the jaw 20 about its pivot in a counter-clockwise direction as seen in Figure 1 it cannot go further than the position shown in Figure 1 because of the hook portion 27 engaging the strap 17. In many instances this relationship of the parts is highly desirable for the attachment of the finding to the ornament 14, as the jaw cannot press against the ornament. In any event the article which is to be gripped between the jaws 14 and 20 will be thicker than the space 30 shown between the ornament 14 and the jaw 20. The jaw 20 is shown as having a bulging portion 29 at its upper end which serves as a convenient means of providing a rounded surface for engagement with the ear lobe or other article to be clasped and also serves as a convenient handle portion for opening the device.

In Figure 2 the jaw 20 is shown as swung to its opening limit of position. As the jaw is swung from the position shown in Figure 1 to the position shown in Figure 2, the tongue 25 will slide along the strap 17 and its corrugation will serve to give this movement a step-by-step action so that it might be stopped at any particular location which will apply a desired amount of pressure upon the ear lobe but will not easily move from this adjusted position. As it is swung to open position, however, beyond the engagement of the corrugated portion 28 with the

strap or bar 17, the strap engages the smoother portion of the spring tongue 31, and as this portion is engaged, the spring tongue while still pressing against the bar is guided by the spring bar so that its outer end 32 will engage the abutment edge 19 of the opening 15 and will limit the movement of the jaw 20 with reference to the mounting member 10 against any further relative movement in this opening direction. This position also may be of convenience for the attachment of the side wall 13 to some particular type of ornament. This arrangement also serves by limiting the opening movement to prevent the spring tongue 25 from being forced beyond its elastic limit in an opening movement, which might otherwise occur if the opening movement were not limited.

I claim:

1. A finding for a clasp comprising a sheet metal mounting member having spaced end walls and a bottom wall, between said end walls with an opening through the bottom wall so located as to be spaced from one marginal edge of the bottom wall in its extent between said end walls to provide a strap, said opening providing an abutment along the edge opposite said strap, a jaw pivotally mounted in said end walls, a spring tongue carried by said jaw and engaging said strap to urge the jaw when in certain positions about its pivotal axis away from said strap, said strap being offset from the plane of the stock of the bottom wall along an extent at least equal to the width of the spring tongue with the amount of offset being substantially the thickness of the spring tongue, said tongue being so shaped that as it slides along the strap it will be guided by the strap into engagement with said abutment to limit its opening swinging movement.

2. A finding for a clasp as in claim 1 wherein said spring tongue is corrugated in a direction parallel to its pivotal axis to provide notches to engage said strap.

3. A finding for a clasp as in claim 1 wherein said tongue is provided with a flange at its end forming a hook to engage said strap and limit swinging movement of the jaw in the other direction for convenience in positioning the jaw relative to the mounting member during attachment of the mounting member to an ornament.
